ELASTIC FABRIC AND METHOD OF
MANUFACTURE THEREOFPhilip Ernest Frank Clay, Radcliffe-on-Trent,
England

Application October 11, 1949, Serial No. 120,685

Claims priority, application Great Britain
January 31, 1949

7 Claims. (Cl. 139—421)

1

This invention relates to a new or improved elastic fabric; the expression elastic fabric as used herein means and includes fabric incorporating elastic (India rubber) thread, or thread having similar properties in so far as concerns extensibility.

It is known to make fabric incorporating elastic (India rubber) thread but heretofore it has been customary to introduce the elastic and inelastic threads under tension (the elastic threads consequently being stretched); as the fabric is made the elastic threads relax so that the ultimate width of the fabric is reduced and the inelastic threads necessarily kink; these are definite disadvantages.

An object of this invention is to overcome these disadvantages and to enable new or improved effects to be obtained in elastic fabrics.

The invention accordingly provides a method of making a textile thread intended primarily for incorporating in elastic fabric for the attainment of the aforesaid object, comprising wrapping at least one thread of inextensible textile material around a core which is removable as by chemical means. A plurality of said inextensible threads may be wrapped round the core successively in opposite senses and, for example, two inextensible threads may be wound helically with a long pitch and one in each opposite sense round the core.

The invention further provides a novel textile thread intended primarily for incorporation in elastic fabric, made by the method aforesaid so as to comprise one thread of inextensible textile material wrapped round a core, or a plurality of threads of inextensible textile material wrapped round a core in opposite senses, the core being removable as by chemical means after incorporation in an elastic fabric.

From another aspect the invention provides a method of making an elastic fabric which is characterised by including in the fabric elastic threads in parallel relationship with textile threads made as above described, and treating the fabric to remove the core material of the textile threads.

Desirably such method of making an elastic fabric may include the incorporation in the fabric of elastic threads maintained in an unstretched condition. Convenient means for achieving this desideratum are disclosed in the specification of United States Patent No. 2,220,213. Alternatively the method of making an elastic fabric may include the incorporation in the fabric of elastic threads in a maintained, predetermined condition of stretch, as disclosed,

2

for example, in the specification of my co-pending patent application Serial No. 120,684 which has issued as Patent No. 2,587,117, dated February 26, 1952. Thus one method of making an elastic fabric including the incorporation therein of elastic thread as disclosed in my said co-pending application may comprise initially stretching the elastic thread, applying thereto at least one helical wrapping of textile thread (to maintain the initial stretch) and superimposing on said helical wrapping a further wrapping of an inextensible thread to inhibit further stretch (i. e. said superimposed wrappings predetermining the initial stretch respectively against relaxation and further stretch) said further wrapping being removable as by chemical means, incorporating in the fabric, in parallel relationship, said elastic thread and textile thread comprising at least one thread of inextensible textile material wrapped round a core which is removable as by chemical means, and treating the fabric to remove said further wrapping of the elastic thread and said core.

It is desirable to employ in the practice of a method of making elastic fabric as last stated, an elastic thread and a non-elastic textile thread of which respectively the further, stretch-inhibiting wrapping and the core are removable as by the same chemical means, preferably a solvent, which is harmless to the elastic thread and its stretch-retaining wrapping and also to the inextensible components in the non-elastic thread. For convenience of removal by means of solvent, a soluble stretch-inhibiting wrapping of the elastic thread and the core of the non-elastic thread may be made of alginate yarn.

The invention further extends to an elastic fabric, made by the method above stated, including elastic and non-elastic threads laid side by side, and having the advantage that the fabric is extensible in the longitudinal direction of said threads and then contractile to its initial dimension without puckering as will be apparent from the following more detailed description.

In order that the foregoing and other objects and features of the invention may be more fully understood, certain embodiments of non-elastic threads and of fabrics made with the aid of such non-elastic threads in association with elastic threads, will be described by way of example with reference to the accompanying drawings wherein;

Figure 1 is a diagrammatic elevation or part of one embodiment of a non-elastic thread according to the invention, prepared for incorporation in an elastic fabric.

Figure 2 is a like view of a modified embodiment of non-elastic thread.

Figure 3 is a like view of a composites elastic thread.

Figure 4 is a similar view of another kind of elastic thread.

Figure 5 is a diagrammatic plan view of one embodiment of elastic fabric after weaving and prior to chemical treatment, according to the invention.

Figure 6 is a like view of a variant of the elastic fabric.

Figure 7 is a like view of a portion of the elastic fabric shown in Figure 5 after said chemical treatment, and unstretched, and

Figure 8 is a like view to Figure 7, showing the fabric stretched.

In the making of a non-elastic thread as shown in Figure 1, which may be effected on any convenient type of machine such, for example, as the type disclosed in British patent specification No. 288,121, a destructible or removable core 1, which may, for example be an alginate thread or yarn, is drawn from a suitable supply, and an inextensible thread 2 made of cotton or any other desired material is wrapped helically, and preferably with a relatively long pitch as shown, around the core 1. Alternatively, a plurality of wrappings may be applied to the core if desired, successive wrappings being preferably applied in opposite senses. For example, as shown in Figure 2 a core 1 may be wrapped first in clockwise direction with an inextensible thread 2a and then in anti-clockwise direction with a superimposed inextensible thread 2b.

For incorporation in elastic fabrics conjointly with non-elastic threads as shown either in Figure 1 or Figure 2, an elastic thread may conveniently be of the type disclosed in United States specification No. 2,220,213 and as shown in Figure 3 of the drawing herein, comprising an elastic (india rubber) thread 3 laid in unstretched condition beside an inelastic thread 4, the two threads 3 and 4 being wound with successive wrappings 5 and 6, applied in opposite senses, so as to combine the elastic and inextensible threads 3 and 4 together and ensure that during the production of a fabric including such threads the elastic thread 3 is maintained in a completely relaxed or unstretched condition. The associated inelastic thread 4 has of course to be removed subsequently from the completed fabric to enable the latter to stretch as required.

An alternative elastic thread for incorporation in elastic fabrics as afforded by the present invention is shown in Figure 4, and consists of elastic thread which is maintained always in a predetermined condition of stretch, while being inhibited during incorporation in the fabric from further stretch, such thread being one of the objects of my aforesaid co-pending application. In such elastic thread a core of india rubber or other elastic 7 is initially stretched and wound with at least one closely pitched wrapping 8 of inextensible cotton or other textile thread which serves to maintain the initial stretch, and thereafter is wound with at least one wrapping, or preferably as shown with two wrappings, having a long helical pitch, of a thread material which is removable by chemical means, such as a solvent, but prior to such removal and particularly during incorporation of a thread in a fabric, serves to inhibit stretching of the elastic core beyond the degree maintained by the wrapping 8.

8. It will be appreciated that in the manufacture of an elastic fabric incorporating jointly non-elastic thread as shown, for example, in either Figure 1 or Figure 2 and an elastic thread 5 as shown for example in either Figure 3 or Figure 4, it is desirable to employ threads whereof the removable core 1, in the one case, and the removable stretch-inhibiting thread 4, or alternatively threads 9 and 10, in the other case, are removable by the same chemical means, which likewise is harmless to or has no deleterious effect on the remaining threads, namely the thread 2 or threads 2a and 2b of the non-elastic component and the elastic core 3 or 7 and the wrappings 5, 6 or 8 of the elastic component.

Preferably chemically removable elements are soluble in the same selective solvent.

A fabric incorporating non-elastic and elastic threads as aforesaid may be produced according to the method of the present invention on any suitable machine such as weaving looms, knitting machines, or lace machines, and there may be any desired relationship between the elastic and inelastic threads. By way of example of a fabric produced according to the method of the present invention there is shown in Figure 5 a woven fabric produced on a loom wherein alternate picks or weft threads 11 are constituted by elastic threads as shown in Figure 4, and the other picks or weft threads 12 are constituted by non-elastic threads as shown in Figure 2. In Figure 5 warp threads 13 are shown as ordinary inextensible, non-elastic threads, but it will be appreciated that such warp threads may if desired consist of any kind of elastic thread or mixtures of elastic and non-elastic threads, for example, similar to the weft threads 11 and 12 as shown.

Figure 6 shows a portion of a like woven fabric in which, however, the elastic threads 11 and non-elastic threads 12 are laid in parallel relationship in groups each comprising two threads of the same kind.

It will be evident from consideration of Figures 5 and 6 that, in the course of weaving, stretching of the elastic threads 11 is inhibited by the external wrappings 5 and 6, while the tension of the irremovable components 2a, 2b of the non-elastic threads 12 is controlled by the presence of the inextensible, but subsequently removable, cores 1.

After a fabric such as shown in Figure 5 or Figure 6 has been made it is subjected to a chemical process to remove the destructible components 1 of the non-elastic threads and 9, 10 of the elastic threads; or alternatively of the inelastic core 4 of a thread such as shown in Figure 3 should the latter have been employed instead of an elastic thread such as shown in Figure 4. The fabric may, for example, be immersed in a suitable bath containing a suitable chemical and the said chemical will destroy the removable threads but have no effect on the remaining threads; evidently such chemical may be of a suitable selective solvent.

As a result of such treatment a fabric, for example, as shown in Figure 5 on completion of weaving, is modified to a condition as shown in Figure 7. By virtue of the initial condition of relaxation of the elastic thread (when a kind of elastic thread such as shown in Figure 3 is employed) or of maintained, predetermined stretch of the elastic thread (when an elastic thread of a kind such as shown in Figure 4 is employed) the spacing between adjacent warp threads 11 is as shown in Figure 7 maintained to be equal to the

spacing as determined in the loom and as shown in Figures 5 and 6, so that the fabric in its treated condition does not pucker or wrinkle. Further by virtue of the use of non-elastic threads according to the present invention, the residual inextensible components of these threads are greater in length in each pick or weft than the width of the fabric, or more particularly are greater in length between adjacent warps 13 than the normal unextended distance between said warps, as shown in Figure 7; that is to say, the residual threads 2a, 2b lie in curved disposition between the warps so as to avoid any appearance of puckering of the fabric and yet on the application of tension in the lengthwise direction of such threads the fabric is enabled to stretch up to a limit imposed by the length under tension of the threads 2a, 2b, as shown in Figure 8. When stretched to the degree shown in Figure 8, the fabric is of course under tension of the elastic threads 11 and the degree of tension is determined by whether these threads 11 are initially (i. e. in the disposition shown in Figure 7) either unstretched or possessed of a maintained condition of stretch; in the latter case, of course, the contractile force of the stretched fabric is considerably greater than in the former case as is explained in detail in my aforesaid co-pending application.

Evidently by virtue of the improved non-elastic threads afforded by the present invention, and the method of incorporating such threads in elastic fabrics, new or improved effects can be produced in such fabrics.

I claim:

1. A method of making an elastic fabric including incorporating in the fabric, in parallel relationship, elastic threads which each include at least one stretch-retaining close wrapping and at least one soluble element serving to inhibit further stretch, and textile threads which each comprise at least one thread of inextensible textile material wrapped round a core soluble in the same solvent as said elements, and treating the fabric with solvent to dissolve the cores of the textile threads and the soluble elements of the elastic threads.

2. A method of making an elastic fabric comprising producing composite textile threads by wrapping at least one thread of inextensible textile material round a chemically removable core, producing composite elastic threads by laying an elastic yarn beside a chemically removable inelastic stretch-inhibiting yarn and appying at least one close wrapping of textile thread around said yarns, incorporating said composite textile threads in the fabric in parallel relationship with said composite elastic threads, and treating the fabric to remove the cores of the textile threads and the stretch-inhibiting yarns of the elastic threads.

3. A method of making an elastic fabric comprising producing composite textile threads by wrapping at least one thread of inextensible textile material round a chemically removable core, producing composite elastic threads by stretching an elastic yarn, applying to said yarn at least one close pitched textile wrapping for retaining it in stretched condition, and applying to said wrapped

yarn a further wrapping of chemically removable inelastic yarn to inhibit further stretch, incorporating said composite textile threads in the fabric in parallel relationship with said composite elastic threads, and treating the fabric to remove the cores of the textile threads and the stretch-inhibiting yarns of the elastic threads.

4. A method of making an elastic fabric comprising producing composite textile threads by wrapping at least one thread of inextensible textile material round a soluble core, producing composite elastic threads by laying an elastic yarn beside an inelastic stretch-inhibiting yarn soluble in the same solvent as said core and applying at least one close wrapping of textile thread around said yarns, incorporating said composite textile threads in the fabric in parallel relationship with said composite elastic threads, and treating the fabric with solvent to dissolve the cores of the textile threads and the stretch-inhibiting yarns of the elastic threads.

5. A method of making an elastic fabric comprising producing composite textile threads by wrapping at least one thread of inextensible textile material round a soluble core producing composite elastic threads by stretching an elastic yarn, applying to said yarn at least one close pitched textile wrapping for retaining it in stretched condition, and applying to said wrapped yarn to inhibit further stretch a further wrapping of inelastic yarn soluble in the same solvent as said core, incorporating said composite textile threads in the fabric in parallel relationship with said composite elastic threads, and treating the fabric with solvent to dissolve the cores of the textile threads and the stretch-inhibiting yarns of the elastic threads.

6. An elastic fabric made by the above method of claim 1, including in parallel relationship unstretched elastic threads and relaxed inelastic threads.

7. An elastic fabric made by the method of claim 1, including, in parallel relationship, elastic threads maintained in partly stretched condition and free for further stretch, and relaxed inelastic threads.

PHILIP ERNEST FRANK CLAY.
